TREATMENT OF BLOOD

Ivan A. Parfentjev, Nyack, N. Y., assignor to
 Lederle Laboratories, Inc., New York, N. Y., a
 corporation of Delaware

No Drawing. Application October 21, 1939,
 Serial No. 300,594

1 Claim. (Cl. 167—78)

This invention relates to methods for obtaining plasma from the blood of immune animals.

In the production of antitoxins and the like, the customary procedure entails the bleeding of immunized animals such as horses, pigs, rabbits, etc. To obtain plasma, the blood is led into a receptacle containing a suitable anticoagulant which maintains the fibrin in solution. The blood does not coagulate but the blood cells (erythrocytes) settle to the bottom of the receptacle and transparent plasma collects in a layer over the blood cells. The supernatant plasma layer may be siphoned off and treated as desired. However, the settled blood cells do not pack very firmly and a considerable amount of plasma remains between the blood cells and is difficult to recover.

By washing the blood cells with salt solution, after removing the supernatant layer of plasma, considerably more plasma can be obtained. By this procedure, a considerable increase in the yield of plasma can be achieved. However, this method of processing the blood cells presents difficulties in that the suspension of the cells in saline is such that the cells do not settle out from the liquid. Therefore, in order to separate the cells from the liquid, a basket centrifuge or a cream separator must be used. The use of either of these types of apparatus is objectionable in that the centrifuge requires considerable time and labor and while the cream separator is more rapid than the centrifuge, the action of the separator is such as to break down the erythrocytes and the liquid is more or less hemolyzed. Furthermore, both types of apparatus are very expensive and the elimination thereof is highly to be desired.

I have discovered that the addition of small amounts of gums to the saline used for washing the blood cells causes the blood cells to settle down into a compact mass and by this means the plasma diluted with the salt solution forms a supernatant layer which can be siphoned off from the settled down blood cells. Gum tragacanth is especially convenient for this use since it is effective in very small amounts.

As a typical washing liquid I may dissolve 136 grams of sodium chloride and 80 grams of sodium pyrophosphate in 15.5 liters of distilled water. This solution is adjusted to pH 7.0 by addition of 6.8 cc. phosphoric acid (sp. gr. 1.7). The resulting solution is made up to 16 liters by the addition of sufficient distilled water. There is then added to the solution 48 grams powdered gum tragacanth (0.3%) and the mixture is agitated vigorously to moisten all of the gum. The solution is sterilized in an autoclave for thirty minutes and is then ready for use.

To use this solution, there is added to the blood cells with their associated plasma, after the supernatant plasma is siphoned off in the usual man-

ner, an equal volume of the washing solution. After standing about twenty-four hours, preferably in a cold room, it is found that the blood cells have settled to the bottom of the liquid in the form of a compact mass from which the supernatant layer of plasma diluted with the washing liquid can easily be siphoned off.

I have found that 0.2% or even less of tragacanth is effective for the sedimentation of the blood cells. I may use 0.5% or even more of the tragacanth if desirable although the increased quantities are generally not necessary. In place of the gum tragacanth, I may use 0.5% to 1.0% gum acacia, gum arabic and similar gums. Mixtures of the gums may also be used.

The use of the gums for facilitating sedimentation of the blood cells is effective with the usual types of anticoagulants such as the sodium and potassium oxalates, citrates, etc. The gum is especially valuable when sodium pyrophosphate is utilized as the anticoagulant as described in my application Serial No. 300,595 filed October 21, 1939. The use of sodium pyrophosphate prevents the cells from becoming as fragile and as easily broken as is the case when oxalates or citrates are used as the anticoagulants.

In washing the blood cells, the washing liquid is preferably an isotonic or hypertonic salt solution which should be neutral or slightly alkaline, e. g. about pH 7-7.5. In addition, the washing solution should contain a small amount of an anticoagulant, such as the pyrophosphate in the specific example described.

As will be seen from the above, the use of the gums in washing the plasma from the blood cells avoids the necessity of using expensive apparatus and, at the same time, prevents hemolysis to give a usable, diluted plasma which represents an increase from 10% to 30% in the yields of plasma as compared with a process which does not involve the washing treatment.

It will be obvious that my process is subject to minor changes and variations other than those described without departing from the spirit and scope thereof.

I claim:

A process of obtaining increased yields of plasma from blood which comprises mixing blood with an anticoagulant, permitting the blood cells to settle, separating the supernatant plasma from the settled blood cells and associated plasma, mixing the blood cells and associated plasma with a substantially neutral sodium chloride solution containing an anticoagulant and not more than 0.2% of gum tragacanth, allowing the mixture to stand in the cold until the blood cells settle to a compact mass and removing the diluted plasma from the settled blood cells.

IVAN A. PARFENTJEV.
